UNITED STATES PATENT OFFICE.

GEORGE A. LOWRY, OF NEW YORK, N. Y., ASSIGNOR, BY MESNE ASSIGNMENTS, TO FABRICORD, INC., TRUSTEE, OF NEW YORK, N. Y., A CORPORATION OF NEW YORK.

METHOD OF CLEANING HEMP AND OTHER FIBROUS PLANTS.

Application filed September 30, 1924. Serial No. 740,705.

This invention relates to a method of separating the fibrous portions from the woody parts of fibrous plants, of which hemp is an example. More specifically, the invention 5 relates to a mode of treatment for fibrous plants whereby the woody or pithy material is eliminated from the plant fiber with practically no loss of fiber and whereby the fiber is obtained in substantial streamers of ribbon-like shape.

I accomplish this purpose, broadly, by causing the fiber to be loosened at one end of the plant stalk and at the same time causing the loosened fiber and freed woody stalk 15 to be sharply deflected from its axial path of travel as the stalk is constantly moved forward. This action causes a constant vibration and jarring of the active end of the stalk, which results in freeing the fiber 20 and breaking the freed stalk in short lengths to be thus eliminated from the entrained fiber. In other words, the end of the plant stalk is violently vibrated by, for example, striking it quick, sharp blows, which vibration or jarring action causes the fibers to 25 loosen. The loosened fiber is pulled laterally off the stalk to be peeled from the stalk end and the stalk is thereby fed forward and broken off in short lengths. As the bared 30 woody stalk is advanced it is broken out by pieces and is thus eliminated from the deflected moving fiber mass. This vibration and constant change of the end stalk acts favorably to constantly loosen additional 35 fiber materials as the stalk is advanced and pulled forward thereby. The loosened fiber is thus in effect stripped from the freed woody core, and the core is laid bare and broken off after the fiber is stripped therefrom, in the manner stated. The effect of this 40 action is in part shown in the accompanying drawing. This drawing shows, in a more or less diagrammatic manner, the effect of subjecting plant stalks of, for example, hemp, 45 to my mode of treatment and operation; and while the drawing is made from actual samples of plant stalks having undergone my mode of treatment, the representations are to be taken as illustrative and not in a 50 limiting sense.

Referring now to the drawing—

Fig. 1 is a plan view of a portion of a hemp stalk, the end of which has been subjected to my mode of treatment.

Fig. 2 is a side elevation thereof.

Fig. 3 is a forward end view; and Fig. 4 represents a portion of the fiber somewhat enlarged.

Where the fiber producing plant, as for example the hemp stalk 10, represented in 60 Figs. 1 and 2, is subjected to my mode of treatment, the fiber 11 is first loosened from the woody stalk part 12. It is then deflected or pulled at a substantial angle to be thus stripped from the loosened core 12. This 65 core is at the same time also deflected and, as it is brittle, is broken into short lengths 13 to be thus eliminated from the mass of more or less ribbon-shaped fiber. These 70 fibers are generally in long streamers, which not infrequently are of the full length of the plant stalk from which they have been separated by my mode of procedure. There is, further, no loss of fiber as the fiber is all removed from the woody core of the plant 75 stalk and is completely separated therefrom. The mode of operation above described may be carried out by hand, or it may be practiced by any suitable machine, such for example, as I have described in my copending 80 application, Serial No. 740,706, of even date herewith.

In describing my invention, I have named hemp as a typical example of fibrous plant upon which my new method is very satisfactory and effectively practiced, but I do not thereby desire to be understood as thus limiting myself, as my method is applicable to any fibrous plant from which the fibers, and in particular the bast fibers, are to be 90 removed.

What I claim, therefore, as new and useful, of my own invention and desire to secure by Letters Patent, is:—

1. The method of peeling the fibrous skin 95 from the core of fiber bearing plants, which comprises pulling the skin at an angle to the core to thereby strip said core unbroken, and then breaking said core.

2. The method of separating fiber from a 100 fiber bearing plant, which comprises causing said fiber-bearing plant to be moved endwise, and while thus moved causing the fiber to be deflected from the path of the moving plant, thereby stripping the fiber from its 105 unbroken core, and then breaking the core.

3. The method of separating fiber from 110 fiber-bearing plant stalks which comprises causing said plant stalks to advance endwise, and while so moving causing the ends

of said stalks to be freed of the fiber and the freed stalk ends to be disrupted, thereby loosening the fiber from the core and removing the woody core after the fiber has been 5 peeled therefrom.

4. The method of separating fiber from fiber-bearing plant stalks, which comprises causing said plant stalks to be moved end-
wise by a pull on the fiber to peel said fiber
10 from the core and while so moving said stalks, causing the ends of the stalks to be broken by disruptive action, thereby loosening the fiber.

5. The method of separating the fiber from the woody core of fiber-bearing plant stalks, 15 which comprises laying bare the core of said stalks and repeatedly deflecting the bared end of said stalks in one direction to break the same while pulling aside the fiber and thereby causing the stalks to be pulled forward by the deflected fiber and stripped from its fiber.

In testimony whereof I have hereunto set my hand on this 18th day of September A. D., 1924.

GEORGE A. LOWRY.
